UNITED STATES PATENT OFFICE.

ALOIS FREIHERR VON GILLERN, OF VIENNA, AUSTRIA-HUNGARY.

CURVED LACING-GUIDE FOR SHOES, CORSETS, AND SUCH LIKE.

1,081,061.

Specification of Letters Patent.

Patented July 2, 1912.

Application filed August 24, 1908. Serial No. 450,091.

To all whom it may concern:

Be it known that I, ALOIS FREIHERR VON GILLERN, a subject of the Emperor of Austria-Hungary, residing at Guldengasse 11^a, Vienna, XIII, in Austria-Hungary, have invented new and useful Improvements in Curved Lacing-Guides for Shoes, Corsets, and Such Like, of which the following is a specification.

10 This invention relates to curved tubular guides for laces.

An object of the invention is to provide a guide preferably made of sheet metal which will hold the lacing in place and 15 which may readily be fastened to the part to be laced.

Another object of the invention is to provide a lacing guide having securing means integral therewith which may readily be attached to the part to be laced without changing the appearance of said part or without projecting it a large extent above the surface thereof.

20 Another object of the invention is to provide a lacing guide by means of which the lacing from one of the guides is directed toward the next guide.

Other objects of the invention will be 25 more fully understood and pointed out by reference to the following specification and to the accompanying drawing.

Figure 1 is a horizontal section through a guide of this kind. Fig. 2 is a perspective view of an embodiment of the invention.

30 Fig. 3 is a bottom plan view thereof. Fig. 4 illustrates diagrammatically the method by which a guide of this kind is secured to the article to be laced. Fig. 5 is a perspective view of a modified embodiment of the 40 invention, and Fig. 6 shows a shoe provided with the lacing guides which form the subject matter of the invention.

The lacing guides consist of a tubular body 1, which is suitably curved and which 45 is preferably provided with enlarged mouth portions 2. These portions serve the purpose of reducing the friction between the lacing running in a sinuous path through the curved guide and the circular edge of 50 the guide body. The tubular member 1 preferably is bent from a sheet of metal or such like, so that an abutting seam 3 is provided, as clearly shown in Fig. 1. The prongs 4 extend from the marginal edges 55 which are in abutment, and as shown in

Fig. 2 these prongs are formed to have a straight portion 5 and a curved portion 6. The straight portions of each pair of prongs consisting of two adjacent companion members are in close juxtaposition. The bent 60 portions, however, are shaped so as to diverge from each other and converge again toward their free end. It is of advantage to provide each of these guides with two pairs of prongs for the purpose of preventing rotation of the guide after the same has been inserted in the part to be laced. In order to provide a tight grip of the companion members of each pair of prongs, one member is provided at the free end with a 70 V-shaped incision 16 and the companion member is shaped to a point 17 adapted to enter said incision after the prongs have been clamped together, as shown in Fig. 3.

In the modification illustrated in Fig. 5, 75 the prongs are not provided with parallel portions but they diverge right from the abutting edge 3 and converge toward their free end similar to the curved portion 6 in Fig. 2. In this modification also the free 80 ends of the prongs are provided with incisions and point shaped projections respectively.

For the purpose of securing a guide of this kind to a piece of leather or other material, the following method may preferably be used. The guide is inserted into an upper die 7 having a recess or cavity 9 to receive the tubular member 1. The prongs are caused to pierce the material 11 so that 85 their free ends rest in another cavity 12 of another die 8. When the upper die 7 is forcibly lowered against the surface 14 of the lower die, the prongs will finally assume the shape shown in the lower part of Fig. 4 90 95 whereby one part thereof is in close contact with the lower surface of the material and another portion of said prongs is folded back against said first named portion. It will be seen therefrom that these folded 100 prongs do not enter into the material so as to damage the same, but they remain only in contact with the respective portion of the companion member. It is also obvious that a removal of the lacing guide after the same 105 has been secured to the material in the way explained is only possible after the prongs have been broken or after they have been bent back to their original shape.

Although I have herein shown only two 110

forms of my invention, I wish it to be understood that I do not desire to limit myself to the exact details of construction as shown.

Having thus described my invention, what

5. I claim as new and desire to secure by Letters Patent is:

1. A lacing-guide made of one single piece of sheet metal with its securing means and consisting of a curved tubular guide-body 10 having pairs of foldable securing feet projecting from the bottom of the guide-body, the central part of the said securing feet curved outwardly, their free ends converging and adapted to lock into each other, sub-

15 stantially as described.

2. A lacing-guide made of one single piece

of sheet metal with its securing means and consisting of a curved tubular guide-body having foldable securing feet arranged in pairs and projecting from the bottom of the 20 guide body, the outer end of one foot of each pair being pointed and the outer end of the other foot of each pair having an insertion into which the point of the opposite foot enters, substantially as described. 25

In testimony whereof I have signed my name to this specification in the presence of two subscribing witnesses.

ALOIS FREIHERR VON GILLERN.
